UNITED STATES PATENT OFFICE.

LUDWIG SCHMIDT, OF MUNICH, GERMANY.

PROCESS OF MANUFACTURING GLYCERIN AND ALKALI SOAPS.

No Drawing.

Application filed February 20, 1923. Serial No. 620,268.

To all whom it may concern:

Be it known that I, LUDWIG SCHMIDT, residing at Munich, Germany, a citizen of Germany, have invented certain new and useful Improvements in the Processes of Manufacturing Glycerin and Alkali Soaps, of which the following is a specification.

The usual processes of obtaining glycerin from fat consist in treatment of soap liquor for that purpose, or in the decomposition of the fat. In both cases only a small yield of more or less dilute, impure glycerin is obtained, and the glycerin requires purification and evaporation, entailing considerable expenditure for chemicals and heat.

The object of this invention is to obtain, by a simple process, a high yield of glycerin in a waterless state, together with a dry soap of useful quality.

This result is obtainable by saponifying the fat with an equivalent proportion of alkali, then thoroughly and briskly drying it and powdering or grinding the dried product, then extracting the glycerin with a volatile, waterless solvent which does not dissolve soap, and finally distilling off the solvent.

The saponification may with advantage be performed with highly concentrated alkali solution, or with dry alkali or alkali peroxide, so that there is a minimum of water to be got rid of. It will be obvious that by the same method glycerin can be extracted from moist soap powder containing glycerin.

The drying may with advantage be performed by placing the saponified mixture, while still warm at the conclusion of the saponifying process, in a good vacuum, and removing the water by suction. The mixture is by these means thoroughly loosened, and becomes sufficiently hard to be easily ground. This hardening of a soap containing glycerin, so that it can be ground, is a surprising result, in view of the fact that alkali soaps produced by the usual methods, even if free from glycerin, retain a plastic consistency even after long storage, and are not capable of being ground. The glycerin cannot be dissolved out of the saponified

mixture till it is wholly dry and granulated, and this is also a fact not to be foreseen.

Any organic, volatile solvent, which does not dissolve dry soap, may be used for extracting the glycerin, as for example acetone, methyl-ethyl-keton, methyl acetate, ethyl acetate, methylal, absolute ether and so on. It is not necessary that the solvent dissolves the glycerin itself, as the lixiviation carries the glycerin with it.

By the drying process, which can be performed rapidly, the saponification products are obtained in a form in which they can be separated easily in a pure state. This results in several advantages over the methods hitherto in vogue.

Clear, waterless glycerin and concentrated, useful soap are at once obtained. The cost of drying the glycerin is saved, and also the cost of chemicals for purification and for salting out the soap. Time is saved, and also apparatus. The soap does not require storage or centrifugal treatment for drying it.

The following is a typical example of the process.

80 kg. of linseed oil are saponified by stirring with 25 kg. of 50% soda lye. As soon as a sample taker is found to be wholly soluble, the boiler is placed under a 10 mm. vacuum, and the mixture is sucked dry, at 80 to 100° C. The water runs off freely and soon the boiler is found to contain a dry, porous, loose mass, crumbly to the touch. This is cooled, ground as finely as possible, and treated for about an hour in an extractor with dry acetone. The acetone-glycerin-containing solution is then completely removed from the extraction, and the acetone is then driven off, leaving clear faintly yellow glycerin, which can be bleached with carbon. The deglycerinized soap left in the extractor is in the form of nearly white, dry powder, and can be used as such, or pressed into cakes.

What I claim as my invention and desire to secure by Letters Patent of the United States is:—

The process of producing waterless glycerin and dry alkali soap which consists in

saponifying fat, to produce a mixture of glycerin and alkali soap, thoroughly drying the saponified product in vacuo, grinding the same, separating the glycerin from the 5 soap by means of a volatile glycerin extracting agent which does not dissolve the soap, and distilling off the extracting agent.

In witness whereof I have signed this specification in the presence of two witnesses.

DR. LUDWIG SCHMIDT.
